US00D891470S

(12) **United States Design Patent** (10) **Patent No.:** **US D891,470 S**
Shan et al. (45) **Date of Patent:** **** Jul. 28, 2020**

(54) **DISPLAY SCREEN OR PORTION THEREOF
WITH GRAPHICAL USER INTERFACE**

(71) Applicant: **23andMe, Inc.**, Mountain View, CA (US)

(72) Inventors: **Peilun Shan**, Redmond, WA (US); **Jie Wei**, San Mateo, CA (US); **Magdalene Misztal**, San Francisco, CA (US); **Brad Kittredge**, San Francisco, CA (US); **Caitlyn Elizabeth Adams**, Redwood City, CA (US); **Afton Kerry Vechery**, San Francisco, CA (US); **Vilia Ingriany**, San Francisco, CA (US); **Timmy Chau**, Emeryville, CA (US); **Claudio Guglieri Lillo**, Walnut Creek, CA (US); **Sampo Aleksi Jalasto**, Mountain View, CA (US); **Joel Parsons**, Helsinki (FI); **Jesse Jouni Sakari Maula**, Menlo Park, CA (US)

(73) Assignee: **23andMe, Inc.**, Sunnyvale, CA (US)

(**) Term: **15 Years**

(21) Appl. No.: **29/684,364**

(22) Filed: **Mar. 20, 2019**

Related U.S. Application Data

(63) Continuation of application No. 29/665,515, filed on Oct. 4, 2018, which is a continuation of application No. 29/599,189, filed on Mar. 31, 2017, now Pat. No. Des. 847,149, which is a continuation of application No. 29/543,054, filed on Oct. 20, 2015, now Pat. No. Des. 788,123.

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The dashed broken lines in the FIGURE show a display screen or portion thereof, and form no part of the claimed design.

The dot-dash broken lines in the FIGURE and the area between the dot-dash broken lines and the dashed broken

(Continued)

lines show portions of the graphical user interface that form no part of the claimed design.

1 Claim, 1 Drawing Sheet
